UNITED STATES PATENT OFFICE.

OWEN L. WHITEMAN, OF HAYDENVILLE, MASSACHUSETTS, ASSIGNOR TO HIMSELF AND CHESTER B. HOSFORD, OF SAME PLACE.

VALVE.

SPECIFICATION forming part of Letters Patent No. 351,142, dated October 19, 1886.

Application filed May 29, 1886. Serial No. 203,607. (No model.)

To all whom it may concern:

Be it known that I, OWEN L. WHITEMAN, of Haydenville, in the county of Hampshire and State of Massachusetts, have invented a new and Improved Valve, of which the following is a full, clear, and exact description.

My invention relates to certain improvements in valves of that description known as "straightway" or "gate" valves.

It consists in the manner in which the gates are suspended on the carrier, whereby a rotating or rocking adjustment is obtained, and in which each gate has a motion opposite to the other, yet in the same direction—the one a horizontal and the other a perpendicular rocking motion—as will be hereinafter fully described and claimed.

Reference is to be had to the accompanying drawings, forming a part of this specification, in which similar letters of reference indicate corresponding parts in all the figures.

Figure 1 is a side elevation of my valve, partly in section; Fig. 2, a bottom view, partly in section, illustrating the manner in which the gates are suspended upon the carrier. Figs. 3 and 4 are detail views of the under sides or backs of the gates; and Fig. 5 is a detail view of the carrier, showing the bearings upon which the gates are hung.

The letter A indicates the valve case, and R the stem; S, a hand-wheel, by which the stem is operated, and T the usual gland or stuffing-box through which the stem passes.

B designates the carrier, which is interiorly threaded to the stem R, as shown, all as in the usual construction. This carrier B is provided at its extreme lower end, upon the one side, with lateral projecting arms B' B', whose outer surfaces are rounded off on a circle, being U-shaped in cross-section. Upon the opposite side of carrier B a recess or slot, C, is formed slightly above the line of the upper or flat surfaces of the lateral projecting arms B' B', as shown in Fig. 5, and penetrating to about one-half its diameter, forming thereby a circular bearing, G, which extends downwardly slightly below the line of the lateral projecting arms B' B'.

D D' indicate gates having suitable closing

disk-faces d d', and E E' the slightly inclined seats, against which the gates close.

F F' indicate the backs of the gates, which confront one another when in position within the valve.

Upon the back F of gate D is cast a square projection, a, formed with a semicircular groove, a', to receive the body of the carrier, and with a cross semicircular groove, a'', to fit upon the arms B' of the carrier, as shown in Fig. 3. The back F' of the gate D' is provided with a square projection, f, centrally in the face of which is a square recess, g, of semi-cylindrical form in cross-section, to receive the circular bearing G upon the carrier B. Semicircular grooves f' are formed in the upper and lower sides of this square projection f, to admit the passage of the screw-stem R. (See Fig. 4.) Thus the carrier B, being recessed or slotted on the one side, forms, as it were, a shelf, upon which, by means of the upper or lateral side of the recess g, the disk D is suspended, while upon the opposite side the lateral projecting arms B' form the support and bearing for the disk D'. The bearings of both disks being circular, admit of an easy rotating or rocking adjustment of the gates, and as the adjustment of the gates on the carrier is central, the wedging force is applied direct, which keeps them secure under high pressure.

In construction my valve is simple and cheap, yet thoroughly effective.

In the operation of my straight-way valve it follows that each gate has a motion on its carriage opposite to that of the other, while both move bodily in the same direction, the gate D having a rocking motion in a vertical plane, while the gate D' has a rocking motion in a horizontal plane, which admits of the gates adapting themselves to the alignment of the valve-seats. A perfect and easy descent is thus secured of the gates to their seats, and an effective seat procured.

Having thus fully described my invention, I claim as new and desire to secure by Letters Patent—

1. The combination, with a carrier, B, constructed with lateral arms B' B', and recess C, forming a circular bearing, G, of gates D

D', provided upon their rear sides with projections formed with recesses adapted to receive the arms B', and bearing G, substantially as described.

5 2. The carrier B, interiorly threaded to receive the stem of a valve, and provided with lateral projecting arms B' B' upon one side at the lower end thereof, and a rectan-

gular recess, C, penetrating the shell of the carrier upon the other side, above said projecting arms, substantially as shown and described, and for the purpose herein set forth.

OWEN L. WHITEMAN.
